H. HOISINGTON

FASTENING DEVICE FOR SHIELDS

Filed Nov. 22, 1924

Patented Dec. 8, 1925.

1,564,415

UNITED STATES PATENT OFFICE.

HARRY HOISINGTON, OF DAVENPORT, IOWA.

FASTENING DEVICE FOR SHIELDS.

Application filed November 22, 1924. Serial No. 751,719.

(GRANTED UNDER THE ACT OF MARCH 3, 1883; 22 STAT. L. 625.)

To all whom it may concern:

Be it known that I, HARRY HOISINGTON, a citizen of the United States, and a resident of Davenport, county of Scott, and State of Iowa, have invented an Improvement in Fastening Devices for Shields, of which the following is a specification.

The invention described herein may be used by the Government, or any of its officers or employees in prosecution of work for the Government, or by any other person in the United States, without payment to me of any royalty thereon, in accordance with the act of March 3, 1883.

15 The subject of this invention is a fastening for shields.

On mobile gun carriages provided with shields it is desirable to fold the upper part of the shield when the carriage is swung to 20 its limber for traveling.

The principal object of the present invention is to provide means for rigidly and securely holding the top carriage in either raised or lowered position and includes a 25 forked brace hingedly connected to the top shield, its free end carrying a locking device engageable in a keeper or bracket on either side of the main shield.

To these and other ends, my invention consists in the construction, arrangement, and combination of elements, described herein-after and pointed out in the claims forming a part of this specification.

A practical embodiment of my invention 35 is illustrated in the accompanying drawings, wherein:

Fig. 1 is a front view showing the top shield in lowered or traveling position;

Fig. 2 is a rear view showing the top 40 shield in the raised or firing position;

Fig. 3 is a view in side elevation of the shield as shown in Fig. 2;

Fig. 4 is a detail rear elevation of the brace;

Fig. 5 is a side view thereof;

Fig. 6 is a detail view of the plunger; and

Fig. 7 is a detail view of the rear bracket.

In carrying out the invention, there is provided a main shield 11 on which is 50 hinged a top shield 12 which may be divided in certain types of guns. When the gun is in action it is obvious that the shield whose function is to protect the gunners and the delicate instruments on the gun, is in the

raised position while when the gun carriage 55 is in transit the top shield is in the lowered or folded position.

For the purpose of securely holding the top shield or shields in adjusted position there is provided a forked brace 13, the forks 60 pivoted on a rod 14 which is mounted in a pair of brackets 15 secured to the top shield 12. The free end of the brace is centrally bored to receive a plunger 16 and plunger spring 17. The plunger is adapted to be 65 manually retracted in the bore by means of a pin 18 passing transversely therethrough and working in aligned blind slots 19 in the brace. The pin 18 also serves to prevent loss of the plunger. 70

Mounted on both the front and rear sides of the main shield 11 are brackets or keepers respectively 20 and 21 preferably secured by rivets and formed with an aperture 22 for receiving the plunger 16. 75

In the views shown the rear keeper 21 is provided with a transverse projection 23 engageable in a notched edge 24 on the brace when the brace is fastened in place. This provision is made to steady the top shield 80 when in the raised position and to serve as an auxiliary catch or securing means in the event the plunger spring is rendered functionless. It will be readily apparent that a spring catch may be substituted for the projection 23 and that if desired a similar construction might be provided on the reverse side of the brace and on the front keeper. 85

While in the foregoing there has been illustrated and described such combination 90 and arrangement of elements as constitute the preferred embodiment of my invention, it is nevertheless desired to emphasize the fact that interpretation of the invention should only be conclusive when made in the 95 light of the subjoined claims.

I claim:

1. In combination with a main shield for guns, a top shield foldable thereon, brackets on one side of the top shield, a rod mounted 100 in said bracket, a brace having forks pivoted to the rod, the free end of the brace formed with a central bore and blind slots in the sides of the brace and in communication with the bore, said portion of the brace further formed with a notched edge, a plunger and spring disposed in the bore, a pin passing through the plunger and slots, and keep- 105

ers formed with apertures to receive the plunger and mounted on both front and rear of the main shield, the rear keeper formed with a transverse projection engageable in the notched edge of the brace.

2. In combination with a main shield for guns, a top shield foldable thereon, brackets on one side of the top shield, a rod mounted in said brackets, a brace having forks pivot-
10 ed to the rod, the free end of the brace formed with a central bore, and blind slots in the sides of the brace and in communication with the bore, a plunger and spring disposed in the bore, a pin passing through the
15 plunger and slots, and keepers formed with apertures to receive the plunger and mounted on both front and rear of the main shield.

3. In combination with a main shield for guns, a top shield foldable thereon, brackets on one side of the top shield, a rod mounted in said brackets, a brace having forks pivot-
20 ed on the rod, a plunger and spring therefor in the free end of the brace, means for manually retracting the plunger, keepers formed
25 with apertures for receiving the plunger and mounted on the front and rear of the main shield, and cooperating means on one of the keepers and the brace for auxiliarily retaining the brace in set position.

30 4. In combination with a main shield for guns, a top shield foldable thereon, brackets on one side of the top shield, a rod mounted in said brackets, a brace having forks pivot-
35 ed on the rod, a plunger and spring therefor in the free end of the brace, means for manually retracting the plunger, keepers formed with apertures for receiving the plunger and mounted on the front and rear of the main shield, and an auxiliarily retaining means
40 for holding the brace in set position.

5. In combination with a main shield for guns, a top shield foldable thereon, a brace

pivoted to the top shield, a plunger and plunger spring mounted in the free end of said brace, means for manually retracting 45 the plunger, keepers attached to both front and rear of the main shield and adapted to receive the plunger, and cooperating means on a keeper and the brace for auxiliarily retaining the brace in set position.

6. In combination with a main shield for guns, a top shield foldable thereon, a brace pivoted to the top shield, a plunger and plunger spring mounted in the free end of said brace, means for manually retracting 55 the plunger, and keepers attached to both front and rear of the main shield and adapt-
ed to receive the plunger.

7. In combination with a main shield for guns, a top shield foldable thereon, a brace pivoted to the top shield, keepers on the front and rear of the shield, and means mounted in the free end of the brace and engageable in the keepers for securely holding the top shield in open or folded position. 60
65

8. In combination with a main shield for guns, a top shield foldable thereon, a brace pivoted on the top shield, and means for securing the free end of said brace on either the front or rear of the main shield. 70

9. In combination with a main shield for guns, a top shield foldable thereon, and a fastening device for holding the top shield raised when in one position of adjustment and lowered when in another position of 75 adjustment.

10. In combination with a body member, an auxiliary member foldable thereon, a fastening device carried by the auxiliary member and engageable on either side of the 80 body member to hold the auxiliary member in open or closed position.

HARRY HOISINGTON.
